INVENTOR
William S. Elliot
By his Attorney
Nelson N. Leonard

UNITED STATES PATENT OFFICE.

WILLIAM S. ELLIOT, OF FLORENCE, MASSACHUSETTS, ASSIGNOR TO UNITED FAST COLOR EYELET COMPANY, OF PORTLAND, MAINE, A CORPORATION OF MAINE.

SHEARING-OUT APPARATUS.

1,188,425.

Specification of Letters Patent. Patented June 27, 1916.

Original application filed December 18, 1914, Serial No. 877,982. Divided and this application filed November 1, 1915. Serial No. 59,078.

To all whom it may concern:

Be it known that I, WILLIAM S. ELLIOT, a citizen of the United States, residing at Florence, in the county of Hampshire and 5 State of Massachusetts, have invented certain Improvements in Shearing-Out Apparatus, of which the following description, in connection with the accompanying drawings, is a specification, like reference characters on the drawings indicating like parts in the several figures.

This invention relates to apparatus for use in making eyelets or other articles of 15 that type which comprises a metallic blank provided upon certain portions with a coating of celluloid or other plastic compound. In my prior application Serial No. 877,982, filed December 18, 1914, of which the present application is a division, there is disclosed a method of manufacturing such articles in accordance with which celluloid or 20 other plastic compound in the form of a sheet molded upon a metallic blank and then the article is completed by being sheared out 25 from the sheet. This method may be carried out with particular advantage in covering simultaneously a large number of blanks.

In carrying out the method of my invention 30 in the manufacture of eyelets there is produced a sheet of celluloid in which is embedded the flange of a metallic eyelet blank while the barrel of the blank projects outwardly from the sheet. Upon one surface 35 there appears molded in celluloid a circular ring of convex surface which surrounds an opening in the sheet while the barrel of the blank and a portion of the under side of the flange appear through an opening in the 40 other surface. As above intimated it is proposed to mold the celluloid sheet upon a number of eyelet blanks at the same time and the article of manufacture so produced 45 possesses many novel and useful characteristics. It comprises a sheet of celluloid having molded on one surface a plurality of raised rings arranged in adjacent rows, and having corresponding rows of openings in the other surface through which project the 50 metallic barrels of the blanks. Sheets of

this kind may be readily handled and transported if desired and the eyelets may be completed by being sheared or punched out of the sheet at any convenient time or place.

I have designed novel apparatus for shearing from the celluloid sheet the completed article and such apparatus constitutes the subject-matter of the present application.

A feature of the invention consists in a holding plate perforated to receive the barrels of the blanks which project from the molded sheet and having a raised shearing surface disposed concentrically about each hole and extending outside the periphery of the covered eyelet flange, together with an oppositely disposed shearing plate provided with shearing surfaces shaped to cooperate with those already discussed.

Another feature of the invention consists in ejecting pins arranged to detach the completed eyelets from the recesses of the shearing plate, and still another feature consists in stripping pins for removing the waste sheet from the projecting shearing surfaces of the holding die plate.

As herein shown the ejecting pins and shearing die surfaces are formed in a pair of relatively movable plates so that the ejecting pins may be maintained in inoperative position during the shearing operation and then 80 may be operated simultaneously to eject the completed eyelets. This construction also constitutes another feature of the invention.

These and other features of the invention will be best understood and appreciated from 85 the following detailed description of a preferred form of apparatus selected for purposes of illustration and shown in the accompanying drawings, in which,—

Figure 1 is a view in perspective of the 90 shearing-out apparatus; Fig. 2 is a plan view of part of the holding plate of the shearing apparatus showing a portion of the sheet to be sheared; Fig. 3 is a sectional view of a part of the shearing-out apparatus 95 with the parts in their initial position, and Fig. 4 is a similar view on an enlarged scale of the parts in the position which they occupy at the conclusion of the shearing operation.

The invention is herein described as ap- 100

plied to the manufacture of eyelets covered with celluloid but it should be understood that this is for convenience in illustration only and that the apparatus may be employed in 5 the manufacture of other articles, such as lacing hooks, studs, or buttons, which are to be covered with celluloid or any plastic compound.

The holding die member comprises a plate 10 50 having a number of flanged tubes 56 set therein. The arrangement of these tubes is similar to that of the dies used for holding the eyelet blanks in the molding operation. The tubes, however, are located slightly 15 closer together in order to allow for the contraction of the celluloid sheet when removed from the molding dies. Surrounding each of the tubes 56 are a number of small stripping pins 58 which work freely in the plate 50 and are normally projected by springs 59 arranged in sockets in a plate 52 which underlies the plate 50.

The coöperating shearing die comprises a plate 60 having formed therein a number of recesses 66 concentrically arranged with respect to the tubes 56. The recesses 66 are of such size as to fit snugly upon the projecting ends of the tubes 56 and to coöperate with the outer edges thereof in shearing the celluloid about the flange of the eyelets. The plate 60 is rigidly secured by the bolts 72 and distance pins 70 in spaced relation to a plate 64. Maintained between these plates and loose on the distance pins 70 is a third plate 62 in which are set a number of ejecting pins 68 one of which projects into each recess 66. A compression spring 74 arranged about each bolt 72 tends normally to move the intermediate plate 62 away from the shearing plate 60 so that the ejecting pins 68 shall be entirely out of engagement with the celluloid sheet.

In practice the shearing die plates are placed in a press of suitable construction 45 such, for example, as is partially illustrated in Fig. 1. As therein shown the stationary bed plate 54 of the press has standards 80 set therein which carry yoke pieces 63. The reciprocating head 84 of the press has 50 secured to it the plate 64 which carries the shearing plate 60 and the ejecting plate 62, as already explained. The ejecting plate 62 projects at its ends beneath the yoke pieces 63 which are so disposed that during the upward movement of the head 84 they encounter the ends of the plate 62 and move it downwardly with respect to the shearing plate 60 against the compression of the spring 74. In this manner the ejecting pins 68 are projected through the opening 66 and eject the completed eyelets which are retained by friction in these openings after the shearing operation. The head 84 comes to rest with the ejecting plate in its lowermost position as clearly shown in Fig. 3.

In carrying out the shearing operation the molded celluloid plate shown in Fig. 2 is placed upon the holding die plate 50 with the eyelet barrels projecting into the openings in the tubes 56 and the molded eyelet flanges supported out to the point at which the shearing is to take place by the flanges of the tubes 56. The press is then started and the head 84 descends. As soon as the ejecting plate 62 is moved out of engagement 75 with the yoke pieces 63 the ejecting pins 68 are moved upwardly into inoperative positions as shown in Fig. 4 and in the continued downward movement of the shearing plate 60 the shearing edges of the recesses 66 co-operate with the shearing edges of the tubes 56 and shear each eyelet from the sheet 30. The head 84 is then elevated and the completed eyelets ejected. In the shearing operation the celluloid sheet 30 is forced downwardly upon the flanged ends of the tubes 56, as shown in Fig. 4, and when the head 84 is elevated the stripping pins 58 lift the perforated sheet off the ends of the tubes. 85

Having thus described my invention, I 90 claim as new and desire to secure by Letters Patent of the United States:

1. Apparatus for manufacturing covered eyelets or the like, comprising a plate with a raised circular shoulder shaped to underlie the entire eyelet flange, provided at its periphery with a shearing surface and at its center with a concentrically arranged opening for an eyelet barrel, together with a coöperating plate having an annular shearing surface. 95

2. Apparatus for manufacturing covered articles, comprising a plate having openings shaped to receive and hold a plurality of metallic shanks projecting in spaced relation from a sheet, stripping means disposed adjacent to each of said openings, and means for shearing the sheet along a line within the stripping means. 105

3. Apparatus for manufacturing covered articles, comprising a reciprocating head, a die plate maintained in spaced relation to the head and having article receiving openings, an intermediate plate movable between the head and die plate, said intermediate plate carrying ejecting pins arranged to play in the openings of the die plate and being provided with sockets opening toward the die plate, and springs located in the sockets of the intermediate plate and tending normally to separate the intermediate plate and die plate. 115 120

4. Apparatus for manufacturing covered articles, comprising a plate having a plurality of flanged tubes set therein with their flanges above the surface of the plate, each tube having a peripheral shearing edge and a central bore to receive the shank of the article to be sheared from a sheet, and a plurality of separate stripping pins ar- 125 130

ranged about the periphery of the flange of said tube and normally standing above the top of the flange.

5. Apparatus for manufacturing covered eyelets or the like, comprising an eyelet holding plate having a raised ring with a surface shaped to underlie the entire flange

of the eyelet and a curved shearing edge, and a coöperating member having a correspondingly shaped shearing opening. 10

In testimony whereof I have signed my name to this specification.

WILLIAM S. ELLIOT.
